his Attorney.

UNITED STATES PATENT OFFICE.

CHARLES D. RUSSELL, OF ST. PAUL, MINNESOTA, ASSIGNOR, BY DIRECT AND MESNE ASSIGNMENTS, TO RUSSELL-WEBER STEEL PRODUCTS COMPANY, OF YOUNGSTOWN, OHIO, A CORPORATION OF DELAWARE.

SPIKE.

Application filed October 6, 1919. Serial No. 328,887.

To all whom it may concern:

Be it known that I, CHARLES D. RUSSELL, a citizen of the United States, residing at St. Paul, in the county of Ramsey and State 5 of Minnesota, have invented new and useful Improvements in Spikes, of which the following is a specification.

My invention relates to improvements in spikes of the class used in railway construction.

Its object is to simplify the spike illustrated, described and claimed in my Patent No. 1,301,173, of April 22, 1919, and particularly to produce a spike which may be rolled 10 more easily and economically from bar steel. These and other objects will more fully hereinafter appear.

In the accompanying drawings Fig. 1 is a perspective view of my improved spike; 20 Fig. 2 is a longitudinal central section of Fig. 1; and Fig. 3 is a cross section on the line 3—3 of Fig. 1.

Referring to the drawings, I have used the numeral 10 to designate the shank of my 25 improved spike, which as usual is provided with an offset head 11. At the end of the shank opposite the head the front and rear surfaces of the spike converge to form a chisel shaped drive edge 12, which is substantially narrower than the body of the spike. A longitudinal concave channel 13 is formed on opposite sides of the shank, and this channel terminates at one end at a substantial distance below the head and at the 30 other end substantially above the chisel edge. In the front and rear surfaces of the shank 10 I form a pair of quadrilateral depressions or mortises 14. Both the side and end walls of these depressions are beveled at 35 top and bottom so that they merge into the surface of the shank and into the base of the

depression on curved lines, as clearly shown in Figs. 1 and 2. The rounded corners thus produced are easier to roll than the angular junctions of the surfaces of the depressions shown in my patent above mentioned, and the small number of depressions simplify the spike. Further, the shorter chisel edge and the termination of the side slots substantially 45 above that edge make more easy and economical the rolling of the spike.

Having described my invention what I claim as new and desire to protect by Letters Patent is:

1. In a spike, a shank, a head on one end of said shank, a driving edge at the opposite end of said shank, curved longitudinal channels in the side surfaces of said shank, and a plurality of spaced mortises in the front and rear surfaces of said shank, said 55 mortises each comprising a quadrilateral depression having inwardly converging side walls.

2. In a spike, a shank, a head on one end of said shank, a chisel edge at the opposite 60 end of said shank formed by the convergence of the front and rear surfaces of the shank, said chisel edge being substantially shorter than the width of said shank, longitudinal concave channels in the side surfaces of said 65 shank, said channels terminating above said chisel edge and below said head, a pair of mortises in said front and rear surfaces, said mortises each comprising a quadrilateral depression, the junctions of the longitudinal 70 side walls of said depressions with the surface of the shank and bottom of the mortise, being curved, and webs between said 75 mortises.

In testimony whereof, I have hereunto 80 subscribed my name to this specification.

CHARLES D. RUSSELL.
